UNITED STATES PATENT OFFICE.

WILLIAM D. SARGENT, OF NEW YORK, N. Y.

PROCESS OF MAKING BRAKE-SHOES.

No. 839,037.

Specification of Letters Patent.

Patented Dec. 18, 1906.

Application filed February 20, 1904. Serial No. 194,610.

To all whom it may concern:

Be it known that I, WILLIAM D. SARGENT, a citizen of the United States, residing at New York, in the State of New York, have 5 invented a certain new and useful Process of Making Brake-Shoes, of which the following is a specification.

My invention relates to the metallic wearing blocks used upon railway brakes, and 10 particularly to methods of making a reinforced brake shoe.

The primary object of my invention is, to 15 construct a brake shoe in which the wearing face, the two sides and the two ends of the body can be formed by casting in a metal mold, while the backing, that is the part 20 having the attaching means thereon, can be made separately of steel plate or cast metal, whereby one mold may be used with a large 25 variety of forms of back, the wearing face, the sides, and the ends being generally of a common standard form and size, while having a great many different forms of backs. Other objects are, to provide for rapid cooling 30 of shoes in which cast metal is intermixed with malleable metal parts; to provide convenient means of packing in expanded metal filling for compound wearing soles; to provide an efficient mode of attaching 35 the back to a cast sole; to provide for making the entire wearing surface of mixed metal; to provide a re-inforced shoe which can be used more than once; to improve the processes of casting shoes, and to generally 40 increase the efficiency and reduce the cost of brake shoes. These objects, together with other advantages which will hereinafter appear, I attain by means of the process hereinafter described and illustrated in the accompanying drawings, in which—

Figure 1 is a central longitudinal section through a brake shoe made according to my process, with compound metal sole and separate back;

Figure 2 is a sectional view of the mold which I use, showing the halves of the mold open;

Figure 3 is a section of the mold closed and a supporting back placed thereon and the 50 expanded metal put in place ready for the pouring of the cast metal filling of the wearing sole;

Figure 4 is a side elevation of the mold;

Figure 5 is a central longitudinal section of 55 a brake shoe made with a modified attachment of the back to the sole;

Figure 6 is a perspective view of an improved steel back for use in this process; and Figure 7 is a section, on line (7) in Figure 6, of the finished shoe. 60

Figure 8 shows a section illustrating the use of my method in forming driver shoes;

Figure 9 shows a skeleton brake block made in the form of common English practice with a sole separately cast thereon; 65

Figure 10 is an under plan of the skeleton block, and

Figures 11 and 12 are respectively an end view and a cross section on line (12) in Figure 9; and Figures 13 and 14 show an under 70 plan and a section of a modification.

In the making of brake shoes it is often advantageous to have the wearing sole thereof composed of two kinds of metal, as soft iron or steel for the purpose of giving it superior 75 drag or frictional quality, and the harder cast iron for purposes of durability and for holding the mass together. By my process it is possible to form a shoe of this character and to combine with such a wearing sole a variety of 80 kinds of supporting back having any desired means of holding the wearing sole thereon. The process is equally useful in making shoes with plain cast iron wearing soles attached to any desired form of back. Forming the backs 85 separately enables the provision of the backs at a low cost and without requiring a large number of different kinds of metal molds and makes it possible to make a great variety of forms of backs with the varying attaching 90 means employed thereon. In its simplest form the proceeding is as follows: Referring to Figures 1 and 3, I provide a back 6, which in this instance is shown as made of malleable casting formed in a sand mold, and is provided with seats for the brake head, an attaching lug 7, and also with recesses 8, which may be in the form of closed boxes with dovetailed openings therein as in Figure 1, or may be simply open slots of the form indicated at 95 9^a in Figure 5, or notches in the side, as in Figure 9.

For casting on the wearing sole I provide a mold, preferably made of metal, of which one part, 12, is made with an open back and has 100 seating surfaces 12^a to receive the edges of the supporting back 6; as shown in Figure 3. Co-operating with this half of the mold is a hinged portion 13, which fits upon the portion 12 in such a manner as to leave open space between the back 6 placed on its seat and the face of the block 13. The mold may then be 105 110

filled with some fragmentary form of malleable metal such as "expanded" steel as shown, stuffing the space as full as required to get the proper proportion between the malleable and the cast metal, and leaving open spaces within the recesses 8, as shown in Figure 3. Thereupon the molten cast iron is poured in through the gate 14 and runways, 16, 16^a, and fills all the interstices between the pieces 10 of malleable metal 10 and also the spaces within the recesses 8 in order to form dovetailed lugs which will hold the compound sole upon the back of the shoe.

It will be seen from Figure 4 that I preferably provide these molds in pairs, connected by branch runs 16^a and pour several at once. The pouring is made endwise and the column of metal in 16 forms a head or pressure, in order to make the shoe very dense, while the 15 multiple inlets allow of rapid filling of the molds. In case the shoe is to be made of the form of Figure 5, it will be understood of course that the back seating portion 12^a of the mold 12, which receives the ends of the back 6 will 20 extend forward enough to cover the openings for the projections 9^a. In forming a long driver shoe, as illustrated in Figure 8, I pack the expanded metal only in the wearing parts 11^b and 11^c and use the open space 11^d as the 25 runway in the mold for the cast metal in pouring. By this means the metal runs in very freely and in the parts where the wear comes, that is parts 11^b and 11^c, the cast metal is cooled very quickly and makes a very hard 30 durable material over the tread and flange, while at the same time saving the expanded metal from injury from excessive heat. In Figures 6 and 7 I have shown a superior form of 35 steel back, in which the lug 7^a is attached by insertion into slits 17 in the plate back 18 and the said back is anchored in the cast body portion by means of the down-turned edges 19. The cast metal covering ends 20 of the lug strap, holds it securely in the slits 17. It 40 will be noted that this plate back is thus continuous without openings and fills the space 12 in the mold, so as to form one complete side of the mold in pouring.

It will be seen that by this method of procedure the molten metal may be applied quite hot and liquid, in which condition it will easily fill the interstices in the expanded metal, and the molten metal coming in contact with the metallic mold on all sides will be very 45 quickly cooled, and this prevents it, in spite of its high temperature, from injuring the quality of the expanded metal. At the same time the sudden cooling of the molten cast metal will give it a very dense close grained 50 structure contributing durability.

It will be observed further, that in the making of the backing, which may be of a more expensive material, a very small quantity of metal is used and that in wearing all 55 most the entire weight of the shoe may be

worn away, when the fragments may be removed and a new sole cast on. For this reason it is preferable to use a backing 6 made of superior quality of malleable iron or steel, which may be used over again. In Figure 5, 70 as it will be seen, the attaching heads 9^a may be knocked through the back of the shoe when all of the face 11 is worn off. In the construction shown in Figure 9, a cast metal backing or a steel or wrought plate may be 75 used. The block 21 which serves as both a brake head and a back for the shoe, has notches 22 and 23 for attachment of the sole by casting thereon, as will be plain from the drawing. Otherwise, instead of notches the 80 base of the block may have an undercut groove all around the side, as shown in under plan in Figure 14, and the shoe sole cast thereon as shown in Figure 13. In this or in any other of the constructions, I may when 85 desired use such strengthening means as the rods or wires 25 buried in the sole 11^a as shown, it being understood that they may be placed on the base of the block 21 or otherwise in the mold as may be convenient, and 90 may take the place of the metal 10. The attaching portions of the wearing sole not being exposed to wear, makes a very durable and efficient and at the same time a perfectly safe shoe. It is of great advantage to have 95 the entire wearing face of the shoe always of the same composition and practically the same throughout its surface of wear upon the wheel. Other advantages will readily occur to those familiar with the art.

Having thus described my invention and illustrated its use, what I claim as new, and desire to secure by Letters Patent, is the following:

1. The process of making brake shoes 105 which consists in providing a back having attaching means thereon, placing the same in a mold in which the said back forms one side, and thereupon pouring in molten metal to fill the space for the wearing portion of the shoe, substantially as described.

2. The process of making brake shoes which consists in providing a back having attaching means thereon, placing the same in a mold in which the said back forms one side, 115 partially filling the space therein with fragments of metal and then pouring in molten metal to fill the interstices between said fragments, substantially as described.

3. The process of making brake shoes 120 which consists in providing a back having attaching means thereon, placing the same in a metal mold in which the said back forms one side, and thereupon filling the space with expanded metal and molten cast iron to form 125 a wearing sole, substantially as described.

4. The process of making brake shoes which consists in placing in a metal mold a supporting back, filling the space for the sole partially with expanded metal, and there- 130

upon filling the interstices between the expanded metal with molten cast iron, substantially as described.

5. The process of making separate wearing soles for brake shoes by providing a metal mold in which one side is formed by a shoe back placed therein, partially filling the space in the mold with pieces of malleable metal and then pouring in a filling of molten cast iron.

6. A brake shoe comprising a supporting back having attaching means, and a wearing sole engaging said means, cast thereupon and composed throughout its entire length and width of malleable metal pieces having the interstices therein filled with cast metal, substantially as described.

15. 7. A brake shoe comprising a cast back having under-cut recesses therein and a

wearing sole cast thereon and in the recesses, 20 consisting of alternate portions of malleable metal and cast metal, said malleable metal and cast metal of the sole extending clear through to the face on all sides of the shoe, substantially as described.

25. 8. A brake shoe comprising a back and a body, said body cast thereon, being composed of mixed malleable and cast metal, and its surfaces on all sides being hardened in casting, substantially as described.

In testimony whereof I have hereunder signed my name in the presence of the two subscribed witnesses.
